UNITED STATES PATENT OFFICE

2,116,491

ANGLE GRINDING SPINDLE

Arthur William Mall, Chicago, Ill.

Application December 19, 1936, Serial No. 116,770

4 Claims. (Cl. 51—170)

My invention relates to improvements in angle spindles and similar devices for supporting grinding wheels.

My invention relates more particularly to angle spindles for use in connection with face grinding on rail joints and other places upon railway tracks.

The principal object of the present invention is to provide an improved angle spindle for supporting a grinding wheel.

A further object is to provide in an angle spindle of the type described an improved handle and guard member.

A further object is to provide in an angle spindle of the type described improved means for permitting an operator to throw his weight on the grinding wheel during operation, thereby causing quicker and more efficient grinding.

A further object is to provide an improved attachment for an angle spindle of the type described whereby all of the above objects can be accomplished.

Other objects and advantages will be more apparent from the following description wherein reference is had to the accompanying sheet of drawings upon which

Fig. 1 is a front perspective view of my improved angle spindle and grinding wheel in working position on a track rail joint;

Fig. 2 is a plan view thereof; and

Fig. 3 is a sectional view through the spindle handle and guard member taken on the lines 3—3 of Fig. 2.

The angle spindle which I have chosen to illustrate my invention may be generally similar to that shown in the patent to Arthur William Mall, granted on August 28, 1924, No. 1,971,790, the only difference being that no water valve and connection therefor is included, inasmuch as water is not used for the grinding wheel to which this application relates.

The unit may include an angle casing 10 having a flexible drive shaft 12 connected thereto for the purpose of driving a vertical spindle 14 suitably mounted therein and provided at its lower end with a face grinding wheel 16. The grinding wheel is provided with a protective top and side covering member 18 which prevents an operator from coming into bodily contact with the side or top portions of the grinding wheel. The angle spindle casing 10 is provided with a handle member 20 extending at right angles to the flexible drive shaft housing 22, and in the devices of the prior art this handle has been employed to

guide and manipulate the grinding wheel during use of the same.

In accordance with my invention I have provided a combined guard and handle extension 24 which is formed with a square block 26 welded to the bottom side thereof. The block 26 may be formed with a tapered opening 28 to fit over the tapered handle 20 and be locked thereon by a set screw 30. The combined guard and handle extension is provided at its forward end with a vertical rod member 32 screw threadedly mounted therein. The member 24 may be generally shaped as shown to be positioned when mounted in an operative manner over one side of the grinding wheel so that pressure may be brought to bear upon one side thereof only. For example, as shown in Figs. 1 and 2, the grinding wheel is being used upon the joint between the rail sections *a* and *b*, and as will be evident, the operator's forearm and hand may be rested upon the same to bring a considerable pressure upon the grinding wheel at the particular point where the grinding operation is taking place.

A great many advantages have been found to result from the above construction. For example, when grinding on a track with this construction, it is possible for the operator to place his weight on the assembly, which eliminates a certain amount of fatigue and enables the operator to grind more steadily. It is also possible to maneuver the grinding wheel to permit grinding on a very small surface of the rails to be ground. The amount of grinding at one point is also regulated, depending upon how much the operator presses down on the combined handle and guard extension.

It is frequently desirable in grinding with a wheel of this type, to grind a comparatively small spot, say 2" long. Without the special handle member it is very difficult to keep the grinding effort on a small spot, the entire grinding wheel being approximately 8" in diameter, which makes it difficult to handle the assembly by the use of the handle 20. With the construction I have provided, the operator may tip the wheel as he is grinding to conform to the contour of the rail surface.

Another advantage of this construction lies in the fact that an operator may more easily lift the grinding assembly with one hand to examine the work, thus saving considerable time for the operator in a grinding operation. It is also obvious that with the additional member 24 secured to the casing handle, the entire assembly may be laid upon its side resting upon the grinding wheel.

shield 18 and the edge of the member 24. This position may be had while the grinding wheel is in motion. In this manner the member 24 acts as a bracket to hold the face of the grinding wheel in a vertical position.

While the exact shape or position of the member 24 may be varied if desired, it will be obvious that to position the same generally as shown and provide a comparatively broad surface, that it 10 makes an ideal arm rest for the operator and permits him to place considerable weight upon the grinding wheel without having any parts of his arm become sore or bruised.

While I have illustrated and described a specific embodiment of my invention, it will be apparent to those skilled in the art that changes and modifications may be made in the exact details shown, and I do not wish to be limited in any particular, rather what I desire to secure and 20 protect by Letters Patent of the United States is:

1. Apparatus of the class described comprising an angle shaped casing having a vertical drive spindle therein, a flexible drive shaft for said spindle extending from a side of said casing, a 25 face grinding wheel secured to the lower end of said spindle, a handle on said casing formed integral therewith and extended horizontally therefrom and a combined guard and platform member secured on the top of said handle and extended over only one side of said grinding wheel.

2. Apparatus of the class described comprising an angle shaped casing having a vertical drive spindle therein, a flexible drive shaft for said spindle extending from a side of said casing, a 30 face grinding wheel secured to the lower end of

said spindle, a handle on said casing formed integral therewith and extended horizontally therefrom and a combined guard and platform member secured on the top of said handle and extended over only one side of said grinding wheel, 5 said combined guard and platform member having a vertical auxiliary handle secured at one end thereof.

3. Apparatus of the class described comprising an angle spindle, a grinding wheel secured to the 10 lower end thereof, a drive for said grinding wheel including a flexible shaft entering the side of said angle spindle, a handle on said angle spindle at right angles to said flexible shaft and a platform member connected to said handle, said platform 15 member being flat and overlying one side of said grinding wheel whereby an operator may bring pressure on only one side of said grinding wheel, said platform having a vertical post member at its forward end to provide a hand grip thereon. 20

4. Apparatus of the class described comprising an angle shaped casing having a vertical drive spindle therein, a flexible driveshaft for said spindle extending from a side of said casing, a face grinding wheel secured to the lower end of 25 said spindle, a protective top and side covering member for said grinding wheel, a handle on said casing formed integral therewith and extending horizontally therefrom, and a combined guard and platform member secured on the top of said 30 handle whereby the entire assembly may be laid on one side resting on the grinding wheel side covering and the edge of the guard and handle member.
